UNITED STATES PATENT OFFICE.

JULIUS M. BEECHER, JR., OF BELLEVILLE, KANSAS.

CRAVAT-HOLDER.

1,087,864.

Specification of Letters Patent. Patented Feb. 17, 1914.

Application filed April 25, 1913. Serial No. 763,597.

To all whom it may concern:

Be it known that I, JULIUS M. BEECHER, Jr., a citizen of the United States, residing at Belleville, in the county of Republic and 5 State of Kansas, have invented new and useful Improvements in Cravat-Holders, of which the following is a specification.

This invention relates to cravat holders; and it has for its primary object the provision of means for maintaining the shape 10 of the cravat and for holding the same in the desired position relatively of the shirt and collar of the wearer.

A further object of the invention is the 15 provision of a securing member which may be adjusted through the neck-band of a shirt and through the button holes of the collar holding the former and the latter in proper closed position.

20 Another object of the invention is the provision of a cravat holder which will embody a guard to hold the ends of the collar against relative separation before the cravat is in its final adjusted position and one 25 which will include means for insuring a snug fit against the neck-band and bosom.

A still further object of the invention is the provision of companion elements of a 30 cravat holder which will have relative interlocking engagement whereby to hold the elements against casual derangement.

With these and other objects in view, the 35 invention consists of certain novel features of construction, combination and arrangement of parts, as will be hereinafter described and claimed.

In the accompanying drawings: Figure 1 is a perspective view of a cravat, showing 40 the application of one element of the holder thereto; Fig. 2 is a perspective view of the other element of the holder; Fig. 3 is a vertical section through the neck-band of a shirt, showing the application of the securing element thereto and illustrating the projection of the shank of the element through 45 the button holes in the ends of the collar; Fig. 4 is a section similar to Fig. 3, showing the parts on an enlarged scale and illustrating the manner of connecting the cravat; Fig. 5 is a section similar to Fig. 4, showing 50 a slightly modified form of the invention; and Fig. 6 is a similar view, showing a further modified form of the invention.

The holder while being designed for use 55 in connection with ties or cravats of any well known form is illustrated herein as

applied to bow-ties, such as the one shown at 8. At the back of the tie and immediately at the center thereof is the element 1 of the holder which is shown to consist of a 60 plate 2 of metal, celluloid, hard rubber or any other suitable well known material having slight resiliency preferably for a purpose to be hereinafter explained. The plate is provided at suitable intervals with openings 3 by means of which it may be sewed to the tie, however, I wish it to be understood that in lieu of such method of connecting the plate to the tie any suitable 65 equivalent or obvious form of fastener may 70 be employed. The plate has stamped therefrom a V-socket 4 having a relatively resiliant wall 5 spaced from the main body portion of the plate and provided with a resilient head or boss 6 which extends into the fastener in the socket so as to intersect 75 the same and to expose the boss for operative interlocking association with the companion securing element or member 7 of the holder. The element 7 is also constructed preferably from a single piece of 80 metal or equivalent material having slight elasticity, and as illustrated the member is folded on itself in its main length to provide an upper head portion 8 and a lower 85 base or head portion 9, the latter being curved forwardly in the direction of its free end so as to be brought into effective engagement with the bosom of the shirt, causing slight pressure to be exerted thereagainst and consequently insure a snug fit 90 of the collar and tie against the neck-band. From the upper portion 8 the fold 10 in the member is extended downwardly and then outwardly, as at 11, to provide a shank 95 which is adapted to be extended through the button-holes in the neck-band and through the button-holes in the collar. At the forward end the shank is provided with a depending V-head 12 having an opening 13 therein for the reception of the boss 6 in the socket of the member 1. The shank 11 is of a forwardly restricted width so that 100 guard shoulders 14 are formed at the juncture of the shank with the head 12, the said shoulders being adapted for confinement against surfaces of the collar at points adjacent to the button-holes whereby to hold the collar ends against casual derangement, 105 as will be understood. The plate 2 of the member 1 is relatively broad and while it is described as being slightly elastic it has 110

such body or rigidity as will contribute admirably toward maintaining a proper condition of the tie.

In applying the device the head portions 8 and 9 of the securing member are first inserted through the button-holes in the neck-band. The collar is then applied to the shirt-band at the back in the usual manner and the ends of the collar are brought forwardly and the button-holes thereof are made to receive the shank 11 so as to cause the head 12 of the shank to lie forwardly from the collar ends. The head 12 is then arranged with its restricted portion downwardly whereby it may be guided into the sockets 5 of the member 1 of the tie and adjusted so as to permit the boss 6 to be properly projected into the receiving passage 13.

If desired the arrangement of the boss 6 and the opening 12 may be reversed as shown in Fig. 5. That is to say, the plate 2 may have the wall 5 of the socket provided with an opening 15 for the reception of a boss 16 formed on the V-head 17 of the securing member of the device.

In the modified form of the invention shown in Fig. 6, the element 1^a of the holder is provided with a socket portion 18 and the member is stamped to form spaced guiding surfaces 19 and 20, the former having an opening 21 therein for the purpose of receiving the boss on the companion elements of the device.

From the foregoing description, taken in connection with the accompanying draw-

ings, the construction and operation of the invention will be readily understood without requiring a more extended explanation.

Various changes in the form, proportion and the minor details of construction may be resorted to without departing from the principle or sacrificing any of the advantages of this invention as claimed.

Having thus described my invention, what I claim is:

A device of the character described comprising a plate having a resilient socket, a member detachably connected with the plate and constructed from a single piece of flat material folded on itself to provide an inner head and an outer head and a connecting shank, said shank being of a forwardly restricted width so that shoulders are formed at the juncture of the shank with the outer head, said outer head corresponding substantially with the inner formation of the socket and insertible therein, means for holding the inner head within the socket, and a base portion formed at the lower end of the inner head and extending downwardly and forwardly and terminating at a point below the plane of the outer head, as and for the purpose specified.

In testimony whereof I affix my signature in presence of two witnesses.

JULIUS M. BEECHER, JR.
